UNITED STATES PATENT OFFICE.

JAMES H. SANDS, OF HOUSTON, TEXAS.

COMBINATION-LEVEL.

SPECIFICATION forming part of Letters Patent No. 279,443, dated June 12, 1883.

Application filed June 7, 1882. (No model.)

To all whom it may concern:

Be it known that I, JAMES H. SANDS, of Houston, in the county of Harris and State of Texas, have invented certain new and useful 5 Improvements in Levels; and I do hereby declare that the following is a full, clear, and exact description thereof, reference being had to the accompanying drawings, making a part of this specification, in which—

10 Figure 1 shows a side elevation of my combined level. Fig. 2 shows a central longitudinal vertical section of Fig. 1. Fig. 3 shows a vertical transverse section of the same on line $\alpha\alpha$. Fig. 4 shows a similar section of my level with 15 a modified form of indicator. Fig. 5 shows an elevation of the eye-piece end of my level.

Letters of like name and kind refer to like parts in each of the figures.

The object of my invention is broadly to provide a combined carpenter's and surveyor's level of a cheap, simple, light, and durable form, and adapted for use as a carpenter's plumb and level or a surveyor's level interchangeably without the removal or change of 25 any of its parts; and to this end it consists in the conformation and arrangement of parts, all as hereinafter more fully described, and specifically set forth in the claims.

In the annexed drawings, A designates the 30 rectangular level-bar, of the usual size and shape of level-bars. The tapering passage B extends longitudinally and centrally from end to end of the bar. At the larger end of this passage is a screw-piece, C, containing the object-glass or lens D, and at its smaller end an eye-piece, E, having the glass F and cross-wires $e\ e$. Midway of its length the bar has a 35 transverse opening or passage, B', closed near each end by the dial or index plates G. In 40 the dial-plates are central openings for the passage of the shaft H, carrying the pointers I I at its outer ends, and having attached to it, just back of each dial-plate, a weight, K. The 45 obvious purpose of these weights fastened to the shaft is to keep the pointers always vertical. As will be seen by reference to Fig. 3, the shaft H is journaled at each end in one of the index-plates, which plates form the only 50 supports necessary for said shaft. Just back of these the shaft is shouldered, as shown, Fig. 3, to bear against the plates, so that all longitudinal play of the shaft is prevented. The

index or dial plates have their circumferences divided into degrees to indicate by the position of the pointer the angle at which the bar 55 is placed with relation to a horizontal or vertical plane. The point of intersection of the cross-wires and the central point of the object-lens are so arranged relatively that they are both in the same line drawn parallel to the 60 edge of the bar. Upon the sides of the bar are pivoted, near the transverse opening, plates L L, arranged to swing over and cover the dial-plates and pointers when they are not in use. They have on their outer ends hooks which 65 engage with pins on the bar to hold the plates in place when swung over the dials. The object-glass and eye-piece may also be provided, if desired, with similar covering-plates, or with slides for the same purpose. 70

In Fig. 4, I show a modified form of indicator, in which the shaft has only one weight and pointer, and is journaled at one end in the single index-dial and at the other in a plate, O, attached to the back of the recess in the bar. 75 The single weight, as is the case with the double form thereof, which I prefer, is attached to the shaft so as to be out of the line of vision through the telescope-tube. The shaft H, I journal in the dial-plates, so as to turn with as 80 little friction as possible. The index-pointer will then show delicately the slightest variation of the edge of the bar from a horizontal or vertical line, and will give, in connection with the graduated index-plate, an accurate 85 measure of the angle of deviation of the edge from such line. My level can then obviously be used not only as a carpenter's level, but as a plumb, and also as a surveyor's level or leveling-instrument. As is evident, for instance, 90 if a distant point be sighted through the telescope-tube in the usual way, the pointers will indicate on the graduated dials the angle of inclination of the line of sight through that point. As is shown, the opening B' is of a 95 diameter equal to more than two-thirds the thickness of the bar and intersects the passage B. The shaft H passes above the line of sight through the tube.

With my construction, without increasing 100 the size of the bar beyond that usual in level-bars, without any external change from the ordinary shape thereof, and without interference with the line of sight through the telescope-

tube, I can heavily weight the shaft and give the weights a long leverage, so as to make my indicator very sensitive.

With the large dials divided into degrees and the correspondingly long pointers, very slight angles or variations of the edge of the bar from true horizontal or vertical lines can be accurately measured.

Most of the ordinary level-bars in the market can easily and cheaply be altered, so as to be in accordance with my invention, without interfering with the spirit-tube or other usual form of level-indicator used with them.

Having thus fully described and set forth my invention, what I claim is—

1. The combined surveyor's and carpenter's level, consisting of the rectangular bar having a longitudinal sighting-passage and the transverse passage intersecting the sighting-passage, and closed at both ends by graduated dial-plates, which form bearings for the index-pointer shaft, provided with a weighted arm attached just back of each dial-plate and hanging down at the side of the longitudinal passage and out of the line of sight therethrough, all substantially as and for the purpose set forth.

2. The combined surveyor's and carpenter's level, consisting of the rectangular bar having a longitudinal tapering sighting-passage provided at its large end with an object-glass and at its small end with an eye-piece carrying glass

and cross-wires, a transverse passage intersecting the longitudinal passage, and closed at each end by an index-dial plate, and a shaft projecting through, journaled in and supported by said plates, and provided at its outer ends with suitable index-pointers, and just behind each plate with a weighted arm hanging down at the side of the longitudinal passage, and entirely out of the line of sight through said passage, all substantially as and for the purpose set forth.

3. The combined surveyor's and carpenter's level, consisting of a rectangular bar having the longitudinal sighting tube or passage near its lower edge, provided with suitable glasses, a transverse passage intersecting the longitudinal one and extending below it, the graduated dial-plates closing the ends of the transverse passage, the index-pointer shaft extending through that passage above the line of sight through the sighting-tube, journaled in the dial-plates, and provided just behind said plates with shoulders, and with weighted arms extending nearly to the bottom of the passage at the sides of the sighting-tube, and adapted to keep the index-pointer always in a vertical position, substantially as and for the purpose set forth.

JAMES HARLEY SANDS.
